M. M. HUSTON

REFLECTOR BOX

Filed Oct. 3, 1921

UNITED STATES PATENT OFFICE.

MARTHA MAE HUSTON, OF SPRINGFIELD, OHIO.

REFLECTOR BOX.

Application filed October 3, 1921. Serial No. 505,063.

To all whom it may concern:

Be it known that I, MARTHA MAE HUSTON, a citizen of the United States of America, residing at Springfield, in the county of 5 Clark and State of Ohio, have invented new and useful Improvements in Reflector Boxes, of which the following is a specification.

The object of the invention is to provide a simple and efficient construction of reflector box for use in connection with signs and particularly illuminated signs and the like and the particular object in view is to provide a knock down construction of the reflector box whereby it may readily be 10 packed and shipped in the folded and compact condition; and with these objects in view the invention consists in a construction and combination of parts of which a preferred embodiment is shown in the accompanying drawings, wherein:

Figure 1 is a perspective view of a reflector box embodying the invention applied in the operative position to the frame of a sign.

Figure 2 is a similar view showing the same from the rear.

Figure 3 is a detail view of the rear wall of the reflector box.

Figure 4 is a central vertical sectional view.

Figure 5 is a detail view on the plane indicated by the line 5—5 of Figure 2.

The reflector box consists of a rear wall 10 of angular or V-form constructed of a single blank of material adapted to be arranged as shown in Figure 3 in a flat condition for packing and storing, and top and bottom walls 11 and 12 of triangular form for closing the space between the rear wall and the plane of the sign frame 13 in which may be arranged any suitable sign filler or diaphragm 14. The material of which the blank forming the rear wall is constructed is preferably pliable or bendable on a vertical line 15 to form an angle to dispose the terminal or wing portions of said rear wall in angular relation to properly reflect and concentrate light supplied by any suitable unit, not shown, upon the sign frame filler or diaphragm 14, a suitable opening or openings 16 being provided in the upper wall to permit of the introduction of such light unit or units. The said top and bottom walls which close the intervals be-

tween the upper and lower edges of said rear wall and the plane of the sign frame are provided with outwardly directed flanges 17 having slots 18 for engagement by thumb buttons 19 mounted on the sign frame. The end edges of the rear wall are notched as shown at 20 for engagement with headed studs 21 on the rear surface of the end or vertical members of the sign frame, and the upper and lower edges of the rear wall are provided with outwardly or rearwardly directed flanges 22 for engagement by the folded edges 23 of said upper and lower walls.

It will be obvious from the foregoing description that in applying the reflector box to the sign frame the rear wall 10 should first be folded or doubled to the angular form indicated in Figures 1 and 2 so as to engage the end notches 20 thereof with the headed studs 21, after which the top and bottom walls should be interlocked at their rear edges with the flanges 22 of said rear wall and then secured by engaging the slots 18 thereof with the thumb buttons 19 whereby the reflector box structure is substantially secured to the frame of the sign. When detached the elements may be folded in a flat parallel condition for shipment in the minimum space.

The arrangement of the rear wall in an angular form and its being made of a single sheet of material folded on an intermediate line provides for the spring action on the part of the rear wall to retain its notches 20 in engagement with the headed studs 21 when the wall is attached and thus provides against rattling if the device is carried on a moving vehicle. Were the rear wall composed of two sections hingedly connected together at the bend, the top and bottom walls would have to be relied on solely to keep the notches in engagement with the studs and there would be likelihood of loose connections with attendant rattling.

Having described the invention, what is claimed as new and useful is:

A reflector box for signs consisting of a rear wall formed with a single blank of sheet material and bent on an intermediate vertical line to form an angle to dispose the terminal portions of the back in angular relation to properly reflect and concentrate light supplied by a light unit, a frame hav-

ing on its rear side edges headed studs with which notches formed in the side rear edges of the back wall engage, the material of the back wall providing spring action tending to keep said notches in engagement with the studs to preclude rattling, and top and bottom triangular walls having interlocking

engagement with the edges of the rear wall at their rear ends and detachably secured to the frame at their front edges.

In testimony whereof she affixes her signature.

MARTHA MAE HUSTON.
